[57] CLAIM

The ornamental design for a photographic filter case, substantially as shown.

DESCRIPTION

FIG. 1 is a top front perspective view of a photographic filter case showing my new design;
FIG. 2 is a left side elevational view thereof;
FIG. 3 is a rear elevational view;
FIG. 4 is a bottom plan view; and
FIG. 5 is a perspective view thereof with the flaps raised to show the interior arrangement.
